STOKER CONVEYER

**Paul A. Ketchpel, Bergenfield, N. J., assignor to
The Standard Stoker Company, Incorporated,
a corporation of Delaware**

Application January 30, 1937, Serial No. 123,120

9 Claims. (Cl. 198—15)

This invention relates to the conveyers for locomotive stokers or like devices and more particularly appertains to the class of stoker conveyers employing several flexibly connected conduits each housing a fuel conveying screw.

It is an object of this invention to provide new and improved means for facilitating the connection and inspection of the conveyer screws in stokers of the type to which reference has been made herein.

A further object of this invention resides in the provision of a new and improved flexible joint structure for a pair of connected conduits adapted to house conveyer screws which are operatively connected by a universal joint within the flexible joint structure for the connected conduits, said flexible joint structure comprising a conduit provided with a spherical portion having a section of such spherical portion removable in order to expose the universal joint between the conveyer screws.

A still further object of this invention contemplates that the section of said spherical portion be arranged for removal through an opening in the firing deck of a locomotive and tender whereby the engine crew may have free access to the interior of the connected stoker conduits from a position on such firing deck.

Other objects, such as the specific construction of parts and their novel relation one with another, will become apparent as the description of this invention is read in connection with the accompanying drawing, in which,

Fig. 1 is a central vertical section through the backwall of a locomotive boiler showing in elevation the stoker in which the present invention is embodied;

Fig. 2 is an enlarged fragmentary central vertical section through adjacent portions of the stoker conduits illustrating the invention in similar section;

Fig. 3 is a plan view of the stoker structure illustrated in Fig. 2 with portions broken away; and

Fig. 4 is a sectional view taken on the line 4—4 of Fig. 2.

Referring to this drawing, 10 represents the locomotive having a boiler backwall 11 apertured at 12 for the introduction of fuel by the stoker S, and by hand when desired, into the firebox 13. The stoker S extends from the tender (not shown) forwardly and upwardly through the locomotive cab deck 14 to the lower portion of the firing opening 12.

The stoker S is of the type employing a forward

or riser section 15 rigidly mounted on the locomotive backwall 11 by means of a support bracket 16 and the flanges 17 extending outwardly from each side of the discharge mouth 18. From the discharge mouth 18, the riser section 15 extends downwardly to a point beneath the cab deck 14 terminating thereat in a spherical seat 19 which receives the spherical element 20 formed with the forward conduit member 21 of the telescopic conduit 22. A rearward conduit member 23 is slidably fitted within the conduit member 21 to form therewith the telescopic conduit 22. A detachable cover or clamp 24, shaped to conform with the radius of the seat 19, is clamped over the upper half of the spherical element 20 to form a universal connection 25 between the riser section 15 and the telescopic conduit 22. Bolts 26 secure the cover 24 at its sides to a flange 34 extending from each side of the seat 19.

The longitudinal movement necessary in the conveyer organization is provided by the telescopic relation of the conduit members 21 and 23. The latter slidably extends into the former to a resting position therein over the bottom portion of the spherical element 20 and over and above the seat 19, whereby the overhanging weight of the conduit member 23 and the conveyer screw 35 therein is supported by the seat 19 of the riser section 15. This construction prevents any sagging or binding of the conduit members 21 and 23.

Within the riser section 15 and the telescopic conduit 22 is suitable means for conveying fuel to the distributor 36 which is disposed at the lower portion of the firing opening 12 in a position to receive fuel from the stoker discharge mouth 18. The distributor is of the well known steam jet type and serves to project the fuel over the firebox grates 37. The conveying means consists of a screw 38 mounted in the riser section 15 and the screw 35 in the telescopic conduit 22. These screws are universally connected at their adjoining ends by a universal joint 39 disposed within the universal connection 25. In the trade, the joint 39 is known as a double universal joint 40 consisting of a connecting link 40 universally attached by pins such as 41, 42 to the jaws 43, 44 of the screws 35, 38, respectively.

In conveying fuel to the distributor 36, it is desirable to do so with a minimum degradation of the lump fuel consistent with the ability of the distributor to handle such lumps of fuel. This result has been attained in the stoker illustrated herein by providing sufficient clearance within the universal connection 25 around the 55

universal joint 39 of the screws 15, 38 and also by maintaining the overall dimensions of the universal joint 39 as small as possible under the expected conditions of service.

5 However, the universal joint 39 is subject to a considerable strain due to its severe operating angle, necessitating its repair and renewal after periods of service. Furthermore, extraneous material in the fuel will oftentimes become 10 wedged between the articulating surfaces of the universal joint 39 causing it to bind and fracture as a result thereof. In carrying out the objects of this invention, means are provided which render convenient the free access into the interior of the universal connection 25 for the purpose of repairing or renewing the joint 39, or for the purpose of freeing the obstructions which may be lodged between the working parts of the joint. As will presently appear, access to the interior of the universal connection 25 is gained by 15 stoker mechanics or engine crews from a position on the cab deck 14, and this will be recognized to be of considerable importance.

The spherical element 20, which is formed with 20 the conduit member 21, is in two sections, the lower section 20a being formed integrally with said conduit member 21 while the upper section 20b is detachably secured thereto in a manner which is now to be described. From its spherical 25 portion 20c, the upper section 20b extends rearward of the universal joint 39 and is provided with a flange 45 at each side thereof, each being arranged to seat upon a corresponding flange 9 at each upper side of the conduit member 21. 30 Bolts 46 detachably secure said upper section 20b to the conduit member 21.

From its upper end, each flange 45 extends 35 forwardly and downwardly approximately to the horizontal plane of the axis of the conduit member 21. Then, the lower edge 47 at each side of the upper section 20b extends forwardly to be received in a seat 48 which opens upwardly at each upper side of the lower spherical section 20a. In this manner, the upper section 20b is centered 40 with respect to the lower section 20a, resulting in the maintenance of a true spherical formation for the element 20 and at the same time preventing lateral movement of the upper section 20b with respect to the lower section 20a during 45 stoker operation.

Access to the interior of the universal connection 25 may be had by removing the bolts 26 which secure the cover 24 to the flanges 34 of the riser 15 whereupon the bolts 46 may be loosened in 50 order to permit detachment of the upper section 20b from the conduit member 21. It will be apparent that the above operations may be performed from a position on the cab deck 14 through an opening 49 which extends slightly 55 to the rear of the upper section 20b to permit withdrawal thereof, as well as the cover 24, through such opening. With the cover 24 and upper section 20b removed, the universal joint 39 becomes readily accessible to a mechanic in 60 the locomotive repair shops. Since the lower section 20a remains in the seat 48, the herein described construction permits the stoker operator to free any obstruction around the universal joint 39 which may occur in stoker operation 65 during road service of the locomotive.

70 I claim:

1. The combination including a pair of conduits, a spherical seat formed in an end of one of said conduits, a spherical element at the adjacent end of the other of said conduits received

in the spherical seat of the first named conduit to form a flexible connection between said conduits, a conveyer screw in the first named conduit, a conveyer screw in the second named conduit, and a universal joint connecting said conveyer screws in approximate coincidence with the flexible connection between said conduits, said spherical element including an upper section detachably connected to said second named conduit.

5 10 15 20 25 30 35 40 45 50 55 60 65 70 75 80 85 90 95 100

2. The combination including a pair of conduits, a spherical seat formed in an end of one of said conduits, a spherical element at the adjacent end of the other of said conduits received in the spherical seat of the first named conduit to form a flexible connection between said conduits, a conveyer screw in the first named conduit, a conveyer screw in the second named conduit, a universal joint connecting said conveyer screws in approximate coincidence with the flexible connection between said conduits, said spherical element including an upper section detachably from the second named conduit, means for detachably securing said section to the second named conduit and means for centering said spherical section in position with respect to said second named conduit.

3. The combination including a pair of conduits, a spherical seat formed in an end of one of said conduits, a spherical element at the adjacent end of the other of said conduits received in the spherical seat of the first named conduit to form a flexible connection between said conduits, a conveyer screw in the first named conduit, a conveyer screw in the second named conduit, and a universal joint connecting said conveyer screws in approximate coincidence with the flexible connection between said conduits, said spherical element including an upper section detachably connected to the second named conduit above the lower section of said spherical element, said upper section extending downwardly to the approximately horizontal plane passing through the axis of said second named conduit.

35 40 45 50 55 60 65 70 75 80 85 90 95 100

4. The combination including a pair of conduits, a spherical seat formed in an end of one of said conduits, a spherical element at the adjacent end of the other of said conduits received in the spherical seat of the first named conduit to form a flexible connection between said conduits, a conveyer screw in the first named conduit, a conveyer screw in the second named conduit, a universal joint connecting said conveyer screws in approximate coincidence with the flexible connection between said conduits, said spherical element including an upper section detachable from the second named conduit and extending downwardly to the approximately horizontal plane passing through the axis of said second named conduit, means for detachably securing said upper section to the second named conduit and means for centering said upper spherical section in position with respect to said second named conduit.

5. The combination including a pair of conduits, a spherical seat formed in an end of one of said conduits, a spherical element at the adjacent end of the other of said conduits received in the spherical seat of the first named conduit to form a flexible connection between said conduits, a conveyer screw in the first named conduit, a conveyer screw in the second named conduit, a universal joint connecting said conveyer screws in approximate coincidence with the flexible con-

nection between said conduits, said spherical element including an upper section detachable from the second named conduit, and means rearward of said flexible connection between said conduits for detachably securing said section to the second named conduit.

5. 6. The combination including a pair of conduits, a spherical seat formed in an end of one of said conduits, a spherical element at the adjacent end 10 of the other of said conduits received in the spherical seat of the first named conduit to form a flexible connection between said conduits, a conveyer screw in the first named conduit, a conveyer screw in the second named conduit, a universal joint connecting said conveyer screws in 15 approximate coincidence with the flexible connection between said conduits, said spherical element including a section detachable from the second named conduit, and means rearward of said flexible connection between said conduits for detachably securing said section to the second named conduit, said means comprising a flange at each side of said detachable section, a flange at each side of the second named conduit arranged to receive a corresponding flange of said detachable section, and screw means engaging 20 said flanges.

7. In combination, a floor, a conveying system having a portion thereof beneath said floor, said conveying system including a pair of conduits, a spherical seat formed in an end of one of said conduits, a spherical element at the adjacent end of the other of said conduits received in the spherical seat of the first named conduit to form a flexible connection between said conduits, such 25 flexible connection being arranged with the greater part thereof beneath the plane of said floor, a conveyer screw in the first named conduit,

a conveyer screw in the second named conduit, and a universal joint connecting said conduits in approximate coincidence with the universal connection between said conduits, said floor being provided with an aperture over the flexible connection between said conduits, said spherical element including a section detachably connected to said second named conduit and arranged for removal from its operative position through the aperture in said floor.

8. As an article of manufacture, a stoker conduit including a tubular portion and a section at one end of said tubular portion integrally formed therewith having substantially the same inner radius of curvature as said tubular portion and being 15 in the form of an arc in transverse cross section, the end of said section remote from said tubular portion having a convex rim formed on and extending about its outer surface, and an outwardly extending attachment flange on that portion 20 only of the marginal edge of said curvate section rearward of said convex rim.

9. A stoker conduit including a tubular portion and a section at one end thereof and integrally formed therewith having substantially the same inner radius of curvature as said tubular portion and being in the form of an arc in transverse cross section, and a detachable arcuate section arranged to form with said first named section a tubular continuation of said tubular portion, the ends of said sections remote from said tubular portion each having a convex rim formed on and extending about its outer surface, and outwardly extending attachment flanges on that portion 25 only of the adjacent edges of said sections rearward of said convex rims.
